Primary Examiner — Khawaja Anwar*Assistant Examiner* — Mojtaba Tehrani(74) *Attorney, Agent, or Firm* — John A. Chionchio, Esq.;
 Ballard Spahr, LLP(57) **CLAIM**

We claim the ornamental design for a rifle, as shown and described.

DESCRIPTION

FIG. 1 is a left side view of our design for a rifle;
 FIG. 2 is a right side view of the design for the rifle shown in FIG. 1;

FIG. 3 is a top view of the design for the rifle shown in FIG. 1;

FIG. 4 is a bottom view of the design for the rifle shown in FIG. 1;

FIG. 5 is a front view of the design for the rifle shown in FIG. 1; and,

FIG. 6 is a rear view of the design for the rifle shown in FIG. 1.

The broken lines depict portions of the rifle that form no part of the claimed design.

1 Claim, 3 Drawing Sheets(56)
